UNITED STATES PATENT OFFICE.

EDWARD C. HAVILAND, OF CHAPPAQUA, NEW YORK, ASSIGNOR TO VAN KANNEL REVOLVING DOOR COMPANY, OF NEW YORK, N. Y., A CORPORATION OF NEW JERSEY.

ELECTRICALLY-OPERATED REVOLVING DOOR.

1,278,145.

Specification of Letters Patent. Patented Sept. 10, 1918.

Application filed September 15, 1913. Serial No. 789,927.

To all whom it may concern:

Be it known that I, EDWARD C. HAVILAND, a citizen of the United States, residing at Chappaqua, in the county of Westchester and State of New York, have invented certain new and useful Improvements in Electrically-Operated Revolving Doors, of which the following is a specification.

This invention relates to electrically operated revolving doors.

In revolving doors now commonly used, with regard to the mode of rotary operation, there are two modes, the more common of the two being the rotary motion given to the door by physical force of the person entering or leaving the door, and the other is one wherein the door is continuously revolved by an electric motor, regardless of any physical force applied by a person.

In cases where the door is continuously revolved, the electric current is obviously being continuously consumed, regardless of the ingress or egress of people through the door. Now, the object of this invention is to provide a means whereby the motor for revolving the door is only put in operation when a person is passing through the door and it consists of means carried by the individual wings of the door that may be either consciously or unconsciously actuated by the person passing through the door to establish electrical circuits, by which the motor is put in operation for only such time as is necessary for the person to pass into or out of the door, thus obviously saving the current and making the operation of doors of this character less expensive.

In the drawings—

Figure 1 is a broken elevation partly in section, showing the upper portion of a wing of a revolving door.

Fig. 2 is an enlarged sectional view of the upper part of the door structure;

Fig. 3 is a section taken about on line 45 *a—a* of Fig. 2;

Fig. 4 is a plan view, partially in section, of the inner end of one of the wings;

Fig. 5 is a vertical section of a portion of one of the wings through the push plate, 50 taken about on line *d—d* of Fig. 6, looking in the direction of the arrow;

Fig. 6 is a rear view of the push plate;

Fig. 7 is a horizontal sectional view taken on line *b—b* of Fig. 5.

Fig. 8 is an elevation of the lower portion 55 of the inner push plate member;

Fig. 9 is an elevation of the motor-actuated arm, showing its connection with one of the wings of the door;

Fig. 10 is a bottom plan view of the arm; 60

Fig. 11 is a broken top plan view of the wing which has operative connection with the motor driven arm;

Fig. 12 is a sectional view of a portion of a wing taken on line *c—c* of Fig. 9, showing 65 the manner of connecting the motor-driven arm with the upper rail of one of the wings.

This invention is applied to a door of the type shown and described in Patent Number 836,843, dated November 27, 1906, and 70 granted to Theophilus Van Kannel, wherein the wings of the door are mounted upon a central spindle and maintained in proper radial position by means of suitable braces or ties, which wings are capable of folding 75 around the shaft, so as to lie in one direction from the center, but since the manner of mounting the wings upon the shaft or supporting the wings is immaterial to the present invention, the mechanism for so-doing 80 will not be described or shown.

Referring to the drawings, particularly to Figs. 1 and 2, the numeral 1 designates the main shaft, upon which the wings 2 are suitably mounted. The numeral 3 designates 85 the ceiling of the door structure and through an aperture 4 in the ceiling extends a sleeve 5 to the upper end of which is attached a gear wheel 6 which may be in mesh with a suitable train of gearing leading to a suitable motor 20', preferably an electric motor and by which the sleeve 5, and parts carried thereby, are rotated. The sleeve is provided, near its lower end, with an integral disk 7, provided in its underneath face, with 90 a recess 8 for the reception of a ring of insulating material 9, in which is embedded two metallic rings 10 in electrical connection through wires 9' and 9" with the two metallic collars 11 and 11', which surround a 100 sleeve of insulating material 12, which is seated upon a shoulder 13 formed on the sleeve 5. The disk 7 of the sleeve 5 is provided with a lateral projection 14 to which is bolted, an arm 15 carrying at its outer end, a roller 16 which is embraced between the lateral halves of a retaining member 17, each half of the retaining member being cut away,

so that when the halves are held together by the screws 18 an elongated slot 19 will be formed for the reception of the headed pindle 20 of the roller 16. By this arm the 5 motor driven sleeve 5 has connection with one only of the wings 2, as shown in Fig. 1, and it is through this connection that all of the wings of the door are revolved, when the sleeve 5 is rotated.

10 Each wing is provided at the inner edge of its top rail with a recess 21 in which blocks 22 of insulating material are seated. In the upper surface of these blocks, I provide metallic plates 23, having attached 15 thereto metallic strips 24 having rounded contact heads 25 which extend through slots 26 in the plates 23. These spring strips are oppositely mounted, as better shown in Fig. 4, so that their contact heads will protrude through the apertures in position to engage the metallic rings 10 carried by the power driven sleeve 5, and thus it will be seen that the contact heads 25 are, during 20 the rotation of the wings, in contact with the rings 10. The plates 23 are secured to the insulating material 22 by means of screws 27 from which run wires 28-28', which are conducted through grooves 29 in the top rail of the wings and down through 25 grooves in the outer stiles of the wings to the push plates.

20 Each wing is provided at the inner edge of its top rail with a recess 21 in which blocks 22 of insulating material are seated. In the upper surface of these blocks, I provide metallic plates 23, having attached 25 thereto metallic strips 24 having rounded contact heads 25 which extend through slots 26 in the plates 23. These spring strips are oppositely mounted, as better shown in Fig. 4, so that their contact heads will protrude through the apertures in position to engage the metallic rings 10 carried by the power driven sleeve 5, and thus it will be seen that the contact heads 25 are, during 30 the rotation of the wings, in contact with the rings 10. The plates 23 are secured to the insulating material 22 by means of screws 27 from which run wires 28-28', which are conducted through grooves 29 in the top rail of the wings and down through 35 grooves in the outer stiles of the wings to the push plates.

Mounted upon the ceiling 3 is an angle iron or bracket 30, to which is attached a block 31 of insulating material. This block 35 has attached to its inner face by means of screws 32, two plates 33 which are provided with ears 24', between which are mounted contact arms 34 provided with rounded heads 35 which are in engagement with the rings 11 and 11'. These contact arms are kept in constant engagement with the rings 11 by means of coil springs 36. From the screws 32 wires 37 and 38 run, the wire 38 running to one of a series of batteries 39 and the wire 37 running to a motor switch 40, which controls the current to set in motion the main driving motor, not shown. This motor, it will be understood, may be of any approved type, and have sufficient 45 power to revolve the door when switched into the circuit by the means that will not be described.

The numeral 41 designates the push-plate which, to all appearances, save with minor 55 exceptions which will appear, resembles the ordinary stationary push-plate now in common use upon revolving doors, but the construction materially differs from the ordinary push plate, as will appear. The push-plate 41 is provided with a rectangular flange 42, which rests in a recess 43, in the outer stile of the wing, and is provided with an elongated rectangular opening for the 60 reception of the movable plate 44, which is hinged to the plate 41 by means of a rod 45,

and around the rod 45 are coiled springs 46 with their upper ends in engagement with the plate 41 and their lower ends in engagement with the movable plate 44 and so arranged that their force will constantly be exerted to keep the plate 44 in the position shown in Fig. 5, wherein no electrical contact is made, nor electrical circuit completed. Attached to the movable plate 44 are the outer ends of the hand rails or push-bars 47, 75 and the inner ends of these rails are pivotally mounted between ears 48 carried by the inner stile of the wings, so that any pressure exerted against the hand rails, which are almost invariably engaged by a person entering or leaving the door, will force the plate 44 inward to complete the electrical circuit with the motor, through the batteries. The inner lower part of the plate 44 is provided with a strip of insulating material 49 seated in a recess in the inner face of the plate. Against this insulating material normally rests one end of a contact point 50, which is carried by a block of insulating material 51 seated in a recess 52 in 80 the outer stile of the door. To this insulating material 51 is attached another contact point 53 and as shown best in Figs. 5 and 7, these two contact points are normally out of engagement. To these contacts run 85 the wires 28-28' leading to the contact strips 24.

In Fig. 5, I have shown a push button 54 with wires 55 running to the bases of the contacts 50 and 53, so that the switch operating circuit, through the batteries 39, may be operated from the push button, if desired, or both devices, that is to say, the swinging push plate and the push button, may be employed together, on the same 105 plate, leaving it optional with the person entering or leaving the door to use either one or the other.

As stated in the foregoing part of this specification, certain parts of the present 110 mechanism are adapted for application to wings that are capable of being folded so as to extend in one direction from the central shaft, and in order to permit this folding, when the usual braces which connect the 115 wings and which are not shown, are detached or released, I prefer the roller and slot connection shown in Figs. 9, 11 and 12. In Fig. 9 the roller is shown in the position it will occupy when the wings are in radial position, 120 with relation to the post or main shaft 1, but when the wings are folded, the roller will occupy the opposite end of the slot and this is because of the fact that the wings in the door of this type, as shown in the patent above 125 referred to, do not turn upon the post, as a center, in folding but rather shift around it.

In operation, the wings of the doors are held in radial position by usual braces. Pressure exerted upon the push-plate, through 130

the hand rails 47, will cause the part 44 of the push-plate to be forced inwardly, completing the circuit, through the contacts 50 and 53, through the wires 28—28' through 5 the contacts 24, through the rings 10, through the wires 9', 9², through the rings 11—11' to the contact arms 34 and through wires 37 and 38, to the batteries 39 and motor switch 40, the result being, when this circuit is established, that the batteries, through the coil 10 of the motor switch, will operate the switch to start the motor. Obviously when the pressure is removed from the hand rails, the 15 springs 46 will restore the plate 44 to normal position, and break the circuit and stop the motor.

While I have shown a gear wheel mounted directly upon the sleeve 5, it will be understood that I do not limit myself to this precise construction as any suitable gearing or method of transmitting the power from a suitable motor to said sleeve, may be employed.

Having thus fully described my invention, 25 what I claim is:—

1. In an electrically operated revolving door, having a plurality of radial wings, the combination of a central spindle, a disk carried by the said spindle and provided with 30 an arm having operative connection with a wing of the door, a source of electrical supply, a motor having a connection with the door for rotating same, metallic contact points carried by said disk and having electrical 35 connections with the motor, contact points carried by each wing and in constant engagement with the contact points upon the disk, circuit controlling means carried by each wing, and in electrical connection with, 40 the contact points carried by the wings, whereby, when the circuit is closed by pressure applied to the circuit controlling means of the wings, the motor is set in motion to revolve the door, and the circuit is broken 45 when pressure is removed, to stop the motor.

2. In an electrically operated revolving door, having a plurality of radial wings, the combination of a central spindle, means connecting the spindle with a wing so that the 50 wing and spindle rotate together, a source of electrical supply, a motor having a connection with the door for rotating same, elec-

trical contact points carried by the spindle, and having electrical connection with the motor, contact points carried by each wing 55 and in constant engagement with the contact points carried by the spindle, a circuit controlling means carried by each wing and in electrical connection with the contact points carried by the wings, whereby, when the circuit is closed by pressure applied to the circuit controlling means of the wings, the motor is set in motion to revolve the door, and the circuit is broken when pressure is removed to stop the motor. 60

3. In an electrically operated revolving door having a plurality of radial wings, the combination of a central spindle, a disk carried by the spindle and connected to one of the wings, a source of electrical supply, a 70 motor having a connection with the door for rotating same, metallic contact points carried by said disk and having electrical connections with the motor, contact points carried by each wing and engaging constantly 75 the contacts upon the disks and circuit controlling means carried by each wing and in circuit with the contact points carried by the wings.

4. In an electrically operated revolving 80 door having a plurality of radially arranged wings, the combination of a central spindle, a disk carried by the spindle and connected to one of the wings, a source of electrical supply, a motor having a connection with the 85 door for rotating same, metallic contact points carried by said disk and having electrical connection with the motor, contact points carried by each wing and engaging constantly the contacts upon the disk and 90 normally outwardly held, circuit closures carried by each wing and in circuit with the contact points carried by the wings whereby, when the circuit is closed by pressure applied to the closure of the wings the motor is 95 set in motion to revolve the door and the circuit broken when pressure is removed to stop the motor.

In testimony whereof I affix my signature in presence of two witnesses.

EDWARD C. HAVILAND.
